(57) **CLAIM**

The ornamental design for a truck body tray floor insert, as shown and described.

DESCRIPTION

FIG. 1 shows a top perspective view of the invention;
FIG. 2 shows a bottom perspective view thereof;
FIG. 3 shows a top plan view thereof;
FIG. 4 shows a bottom plan view thereof;
FIG. 5 shows a front view thereof;
FIG. 6 shows a rear view thereof; and,
FIG. 7 shows a right side view thereof (left side is mirror image).
